UNITED STATES PATENT OFFICE.

BENJAMIN M. DES JARDINS, OF WEST HARTFORD, CONNECTICUT, ASSIGNOR TO UNDERWOOD ELLIOTT FISHER COMPANY, OF NEW YORK, N. Y., A CORPORATION OF DELAWARE.

TYPEWRITING MACHINE.

Application filed February 4, 1925. Serial No. 6,709.

This invention relates to typewriting machines, and is shown in connection with a machine of the type illustrated in a patent to G. G. Going, No. 1,305,091, dated May 27, 1919; although the invention is not limited to this type of machines. In said machine the types are mounted upon the ends of slides, each slide carrying three types; and type-bars are moved against the platen by means of keys.

It is an object of the present invention, in this and other types of machines, to increase the number of rows of keys, or in other words to eliminate one of the usual case-shift keys; and this object is accomplished in a manner that permits a reduction in the number of type-bars, thereby giving substantial advantages, and not only saving in cost and room, but also enabling the type-bars to be directed less obliquely against the platen, thereby improving the type-impressions on the work-sheets.

According to this invention each type-bar is operable by two keys, so that an increase of the number of keys to say forty-two may be accompanied by a reduction of the number of type-bars to say twenty-one, thus gaining substantial advantages.

Each type-bar carries four types, and is operable by depressing either of two type-keys, each key bringing into use two of the types; a shift-key is provided for shifting the platen from lower to upper case position. When the platen is in normal position, depression of one of said two keys will drive the type-bar to the platen, printing a lower-case type, while, if the platen is in an upper-case position, the same type-key will print an upper-case type on said type-bar.

When the other of said two keys is depressed, however, it not only drives the type-bar to the platen, but also automatically shifts the individual type-bar to bring into use the other lower and upper case types thereon. One-half of the type-keys therefore are capable of shifting their own type-bars individually at the printing strokes. One way of accomplishing this individual type-bar shift is to provide an individual shifter for the type-end of the type-bar, and connect said shifter to be operated by the type-key.

The type-bars in the machine shown in said patent are usually arranged radially in

a horizontal position in front of the platen, and have a sliding reciprocatory movement to and away from a common printing point. Due to the magnitude of the angles at which the end type-bars strike the platen, the capacity of such machines has been limited to about thirty type-bars and thirty type-keys, and, in order to provide a full complement of characters, each type-bar with a few possible exceptions, has three types thereon, necessitating the use of two shift-keys, there being one key for each outer course of types. The keys, as shown in said patent, are arranged in three banks or rows which is objectionable in some well-known respects.

A feature of this invention, relates to means to enable the use of a four-bank standard keyboard, in a machine of this kind, although applicable also to other machines. In carrying out the invention the number of type-bars employed (preferably 21) is equal to half the number of character-keys (42) in the keyboard.

Each type-bar is shown in the drawings provided with a lower group of two lower-case types, and an upper group of two upper-case types. The type-key-levers associated with the two lower banks of keys are shown in one arrangement of the invention connected to operate the type-bars in the usual way in this type of machine, to thus cause the lower type of the lower-case group to print. The key-levers associated with the two upper banks of keys also operate the type-bars associated with the two lower banks of keys, and at the same time shift the type-bars individually and automatically to cause the upper type of the lower-case group to print.

In another arrangement of the invention the two middle banks of keys, which are most used, are connected to operate the type-bars only. The upper bank and the lower bank of keys, which are not used so frequently, are connected to also shift the type-bars while they are being actuated towards the printing point.

To bring about the shifting of the type-bars, each key-lever of the two upper banks of keys in the one arrangement, or each key-lever of the two outer banks of keys in the other arrangement, has connected thereto a plunger which embraces the associated type-bar, so that said type-bar may be lifted by

said plunger as the key-lever is actuated, thus selecting the desired type of the type-bar.

A type-guide is provided with which the forward ends of the type-bars co-operate to register the imprint of the type at the printing point. This type-guide is shiftable with each case-shifted type-bar. For this purpose each type-bar shifting plunger is provided with a lug or projection, which lugs engage with a universal bar connected with the type-bar guide to shift the latter to the desired position, so as to be effective to guide the type-bar, at the printing point, in its case-shifted position.

Provision is made to complete the shifting of the type-bar immediately before the type-bar reaches the platen. To this end there is provided a yielding connection between each type-bar shifting plunger and its associated key-lever which enables a further depression of the key-lever to complete the printing stroke after the type-bar has been arrested in its shifted position by suitable stop-devices. By suitably locating the point of attachment of said connection upon said lever, the extent of the printing stroke of the lever exceeds the extent necessary to shift the type-bar, thereby assuring that such shifting is completed before the type-bar prints.

It will be understood that with this arrangement the number of type-bars is decreased with a consequent decrease of the total angle occupied by the type-bars, which makes the angles at which the outer type-bars approach the platen more favorable, in other words, more nearly perpendicular to the platen.

In order to print with the upper-case types, the platen is shiftable to the groups of upper-case types on the type-bars.

The invention is herein illustrated as having a case-shift mechanism of the type shown in the patent to G. G. Going, No. 1,308,411, dated July 1, 1919, with some modifications that are shown in the patent to N. H. Anderson, No. 1,155,635, dated October 5, 1915.

Features of the present invention may be used with other kinds of type-bar machines.

Other features and advantages will herein-after appear.

In the accompanying drawings, Figure 1 is a cross-sectional view in elevation through the center of the machine, showing the type-bar mechanism in its normal position.

Figure 2 is a plan view partly in cross-section, showing the type-bar mechanism and the keys operatively connected in pairs.

Figure 3 is a fragmentary front view in elevation, showing the linkage connecting the type-bars and the keys.

Figure 4 is a cross-sectional view in ele-

vation through the center of the machine, showing the type-bar mechanism in its operated position.

Figure 5 is a plan view showing a modified disposition of the keys operatively connected in pairs.

This invention is shown for example in connection with a "Noiseless" typewriter. The invention is also useful with other varieties of machines. The type-action may, for example, be like that shown in the previously-mentioned patent to G. G. Going, No. 1,305,091, in which there is shown a machine-frame 10 having a keyboard at the front and a movable platen 11 mounted in a platen-carriage 12 at the rear, the latter being controlled in its longitudinal letter-space movement by an escapement mechanism (not shown). Finger key-levers 13 and 13^a are fulcrumed at their ends in a cross-piece 14, and have keys 15 and 15^a. The key-levers are guided in vertical movements by a slotted guide 16, and said movements are limited by stops 17 and 18. The levers have springs 20 between a dependent lug 21 of each lever, and a floating link-plate 22 adjustable by a tie-link 23.

Type-bars 24 are arranged radially in advance of the platen 11 and have reciprocating movements guided between plates 25 and 26. The connection between a key-lever 13 and a type-bar 24 to cause printing when the former is operated, includes a pull wire 27 fastened to the key-lever and connected to a rocking lever 28 fulcrumed to the depending arm 29 of a bracket 30. The lever 28 engages a short arm 32 of a bell-crank lever 33 pivoted on bracket 30. The long arm 34 of said bell-crank lever 33 is connected to a link 35 having at its forward end a weight 36, and at its rearward end a lever 38 pivoted on the bracket 30 and connected to a link 39 pivoted to the type-bar 24. The universal-bar 40 is actuated by a straddling piece 41 on the bell-crank-lever 33. The bell-crank-lever 33 is held in normal position by a spring 42. To hasten the rebound of the type-bar after printing, the arm 43 of the bell-crank-lever engages a pad 44.

In machines such as illustrated in the aforesaid patent to Going No. 1,305,091, in order to limit the degree of obliquity at which the outer type-bars strike the platen, the number of type-bars and keys has been limited to about thirty type-bars and thirty type-keys, each type-bar with possibly a few exceptions, carrying three types. This necessitates the use of two shift-keys, one for each outer course of types, there being one type-key for each type-bar, the keys being arranged in three banks, which is objectionable.

In my present invention I have provided a standard four-bank keyboard having the

usual complement of 42 keys. Said keys are paired and connected to the type-bars in such manner that each type-bar is operable by two keys, either of which may print two characters, as will be shown. The number of type-bars is substantially one-half the number of the keys. Each type-bar is preferably provided with a lower group of two lower-case types 45 and 46 and an upper group of two upper-case types 47 and 48. The type-key-levers 13 associated with the two lower banks of keys 15 are connected to operate the type-bars 24, in the manner already described, to cause the types 45 of 15 the lower-case group to print.

The key-levers 13^a associated with the two upper banks of keys 15^a are each provided with a pin 49. Each pin 49 overlaps a key-lever 13 of one of the two lower banks of 20 keys which has its types 45 and 47 on the same type-bar. When one of the keys 15^a is depressed, the pin 49 on its key-lever 13^a will engage with the key-lever 13 of a type-key 15, depressing the key 15 and its key-lever 13 downwardly, which in turn will drive the type-bar 24 towards the platen. During the downward motion of the key 15^a, means which have been provided between its key-lever 13^a and its type-bar 24 are effective 25 to individually and automatically shift said type-bar and thereby cause its type 46 to print.

To bring about the shifting of the type-bars 24, each of the key-levers 13^a has pivotally connected to it a link 50 slidably mounted in a loop 51 at the lower end of a link 52, which in turn slides in a loop 53 at the upper end of the link 50, and is pivotally connected at 54 to one end of an arm 55 swingable about a pivot 56 on a bracket 57 fixed on a bar 58 of the plate 26. At its other end, the arm 55 is provided with a slot 59 which engages a pin 60 of a plunger 61 which embraces the type-bar 24 and guides 40 its sliding movement. When its key 15^a in one of the two upper banks is depressed, it will pull its link 50 down, and through the reaction of a coupling spring 62 on the link 50, the link 52 will be pulled down, 45 swinging the arm 55 about its pivot 56 and forcing the plunger 61 up, which in turn will lift the type-bar 24 so as to bring the type 46 in position to print. The plungers 61 are guided up and down in slots 63 formed 50 in the arcuate edge of the plate 25 and said slots have their outer ends closed by a bar 64 fastened at its ends to the plate 25 by means of screws 65.

In order to limit the upward and downward movement of the plungers 61, provision is made of lugs 66 and 67 on each plunger 61 to engage a forwardly-extending plate 68 fastened on the plate 26 by screws 69. When a plunger is being moved upwardly by the 65 depression of its key 15^a, its lug 66 will en-

gage the plate 68 prior to the completion of the downward movement of the key 15^a. The yielding connection, due to the spring 62, between the links 50 and 52 enables a further depression of the key 15^a, so that 70 the type-bar 24 will thus have reached its shifted position before the type reaches its printing point. When the key 15^a is released, links 50 and 52 and the plunger 61 return to their normal positions. The 75 plunger 61 is established in its normal position by means of the lug 67 engaging the plate 68. The link 52 is provided with a stop 70 fastened to it, to engage the loop 53 and hold the links 50 and 52 against the reaction of the spring 62 in their normal relation.

The type-bars 24 are guided at one end by projections 71 and 72 on the plates 25 and 26, respectively, and laterally guided 85 by the slotted plate 73 suitably fastened to the plate 26. To guide the type-bars and register the types at the printing point, provision is made of a type-registering guide formed by plates 74 and 75. Means are provided to shift said guide co-relatively with the shifting of the type-bars 24. To this end, the plungers 61 are each provided with a lug 76 underlying a universal-bar 77 fast on arms 78 fixed at one end to a rotatable rod 79 mounted in downwardly-extending arms 80 of the plate 26. The arms 78 have pivotally connected to them at their outer ends upwardly-extending rods 81, vertically movable in a slot 82 of an arm 83 attached to 100 the plate 25. The top and bottom guide-plates 74 and 75 properly spaced apart are fastened to the rods 81. When a plunger 61 is operated to lift its type-bar 24, the lug 76 will engage the universal-bar 77, swinging 105 the arm about its pivot and lifting the rods 81 with the guide-plates 74 and 75 vertically upward. To return the guide-plates to their normal positions, provision is made of springs 84 mounted on the rods 81 between 110 the movable guide-plate 75 and the fixed arm 83, so that when the guide-plate 75 is raised, through the action of the plunger 61 engaging the universal-bar 77, the springs 84 will be compressed, and when the plunger returns 115 to its normal position, the springs will expand and thereby return the guide-plates 74 and 75 and the universal-bar 77 to their normal positions.

In order to print with the upper-case types, the platen is shiftable to the group of upper-case types on the type-bars. This platen-shifting mechanism is similar to that shown in the patent to G. G. Going, No. 1,308,411, but using only one shift thereof. The shift-key 85 has its key-lever 86 pivoted to a lug 87 and is turned upwardly and provided with an arm 90 fulcrumed at its extremity to a link 91, also in turn pivoted to an arm 92 of a lever 93 pivoted to a bracket 125 130

95 mounted on the frame 10 and fixed there-
to by means of its lower rearwardly-extending
arm 96 fastened to the frame 10 by
screws 97. The lever 93 has a rearwardly-
extending arm 98 pivotally connected by a
link 99 to an arm 100 integral with a rock-
shaft 101 trunnioned in the machine frame.
A second arm 102 integral with the rock-
shaft 101 is attached to a link 103 support-
ing a rail 104 on which the carriage 12 is
mounted for movement. When the shift-
key 85 is depressed, the link 103 will be
moved vertically upwardly, thereby lifting
the carriage 12 and bringing the platen in
position to allow the upper group of types
to print. In order to insure vertical move-
ment of the carriage, it is guided by means
of a link 105, shown in the patent to Ander-
son No. 1,155,635, and an upwardly-extend-
ing portion 106 of a tie-rod 107.

To adjust the platen when webs of differ-
ent thicknesses are used, there is a graduat-
ed plate 108 co-operating with an indicat-
ing finger 109 fast to a rearwardly-extend-
ing shaft 110 threaded at 111 into the tie-
rod 107. By movement of the finger 109,
the platen will be moved to or away from
the types.

The arrangement of the keys 15 and 15^a is
not limited to the manner shown in my ap-
plication, but may be arranged in various
ways. In another arrangement (Figure 5)
the two middle banks of keys, which are
most used, are connected to operate the
type-bars only. The upper bank and the
lower bank of keys, which are not used so
frequently, are connected to also shift the
type-bars while they are being actuated to-
wards the printing point.

40 It will be seen from the foregoing de-
scription, that I have provided means where-
by the number of type-bars in a type-writ-
ing machine may be reduced to substantially
one-half the number of keys required to op-
erate the type-bars, and thus I eliminate the
necessity of reducing the keyboard of the
machine in cases when, due to compactness
of the machine or due to the peculiar design
of the type-bar mechanism, it may not be
50 feasible or practical to have as many type-
bars as it would be necessary to provide to
suit the requirements of a standard key-
board.

The type-bar shifting mechanism which
55 forms the subject of this invention, is illus-
trated in connection with a type-writing ma-
chine in which the type-bars are disposed
for rectilinear travel, because this is one
case in which the advantage of having the
60 number of type-bars reduced, and the num-
ber of keys increased, is obvious, as it per-
mits the building of a machine of this type
having a full keyboard, while at the same
time it reduces the striking angle of the out-
65 er type-bars. However, I do not wish to

limit my invention to this type of machine,
as the same features may be used to advan-
tage in any type of machine, especially
when for any reason it is desirable to reduce
the number of type-bars, or to increase the 70
number of keys.

Variations may be resorted to within the
scope of the invention, and portions of the
improvements may be used without others.

Having thus described my invention, I 75
claim:

1. In a typewriting machine having a rev-
oluble platen, the combination of a series
of reciprocable type-carriers, each carrying
a plurality of types and each carrier having
a case-shiftable guide for determining the
direction of its movement toward the platen,
and means including a pair of adjoining
key-levers for variably operating each type-
bar, said means including connections to 85
one lever of each pair to actuate the carrier,
and connections to the other lever to case-
shift a guide and interlock with the first
lever for a joint depression of both levers to
type and case-shift the type-carrier. 90

2. In a typewriting machine having a rev-
oluble platen, the combination with a sys-
tem of horizontally-reciprocable type-car-
riers, each having a plurality of types and
a system of key-levers for operating said 95
carriers, said key-levers associated in pairs,
one pair for each type-carrier, one lever in
each pair being connected for the normal
operation of a type-carrier, of means for
enabling the other lever in each pair to 100
cause a type-carrier to present a different
type to the platen, said means including a
vertically-disposed guide individual to the
type-end of each type-carrier for altering
the typing position of the carrier, said other
key-lever operatively connected to shift said 105
guide, the printing positions of the types
on each type-carrier coinciding with the
printing positions of the types on all the
remaining type-carriers. 110

3. In a typewriting machine having a
platen, the combination of a series of type-
bars, each having a plurality of types there-
on and each type-bar also having guiding
edges to direct it toward said platen, an in-
dividually shiftable bearing for each type-
bar in which said guiding edges move,
means including a pair of key-operated le-
vers for each type-bar for causing said type-
bars to print, and means controlled by one 115
lever of each pair to shift the associated
type-bar by shifting its bearing and thereby
cause the type corresponding to said one le-
ver to print. 120

4. In a typewriting machine including a 125
revoluble platen, the combination with type-
bars, each having a plurality of types there-
on and each type-bar having a reciprocable
movement toward a type-registering guide
at the common printing point, and a series 130

- of key-levers arranged in pairs, one pair for each type-bar and one lever of each pair operative at all times to reciprocate the type-bar, of means to enable the other key-lever 5 of each pair operable to change the angle of reciprocation for the type-bar and simultaneously actuate the first key-lever to type the case-shifted character, said means including a vertical case-shiftable guide for 10 each type-bar, and key-connections to correspondingly shift the type-registering guide.
5. In a typewriting machine including a revoluble platen, the combination with type-bars, each having a plurality of types thereon and each type-bar having a reciprocable movement toward a type-registering guide at the common printing point, and a series of key-levers arranged in pairs, one pair for each 15 type-bar and one lever of each pair operative to reciprocate a type-bar, of means for enabling the other key-lever of each pair operative to change the reciprocating direction of said type-bar to present a case-shifted type and simultaneously operate the first lever to present the case-shifted type to the platen, said means including a type-bar guide vertically reciprocable by connections with its key, and having individual 20 connections for simultaneously shifting the type-registering guide.
6. In a typewriting machine including a revoluble platen, the combination with a series of reciprocable type-bars, each bar 25 having parallel guiding edges for directing it in a substantially horizontal path toward said platen, a plurality of types on each type-bar, and a series of key-levers arranged in pairs for each type-bar, of means operatively connected to one of said levers in each pair to reciprocate a type-bar to type, and other means operatively connected to the other lever of each pair for changing the path of the type-bar and actuate the first 30 lever to project the bar to the platen.
7. In a typewriting machine having a platen, the combination with a reciprocable case-shiftable type-carrier having a plurality of types thereon and a pair of co-operative key-levers, of connecting means whereby one of said levers directly operates said type-carrier to print, connecting means whereby the second lever operates to case-shift the type-carrier and not print, and 35 means operatively engaging the second lever by the first lever, whereby both levers will operate in unison.
8. In a typewriting machine having a revoluble platen, the combination with a radial array of type-bars in front of said platen, each type-bar having a rectilinear movement from said array toward a common printing point, a plurality of types on each type-bar, a series of paired key-operated levers, each 40 lever operable by pressing its own key, means whereby either lever of each pair operates a type-bar corresponding to said pair, and means whereby operation of one lever of each pair displaces the operated type-bar and causes the type corresponding 45 to the operated lever to print, said last-mentioned means including a stop-device to limit said displacement and a yieldable connection between said one lever and the related type-bar, said one lever at the point of attachment of said connection having a movement in excess of the movement required for said displacement, which is thereby completed before the type-bar strikes.
9. In a typewriting machine, the combination of a series of type-bars, each having two types and upper-case complements of said types, and each type-bar also having guiding edges whereby it is directed toward the printing point, a stationary bearing in which one portion of said guiding edges on each type-bar is retained and moves, an individually-movable bearing for each type-bar in which another portion of said guiding edges is retained and moves, a series of paired key-operated levers, means whereby the operation of one of the levers of any pair drives a corresponding type-bar and causes one of said two types thereon to print, means whereby operation of the other lever of said pair also causes said corresponding type-bar to be driven to the printing point, and means whereby operation of said other lever simultaneously shifts said movable bearing of the operated type-bar and thereby causes the other one of said two types to print.
10. In a typewriting machine, the combination of a series of type-bars, each having two types and upper-case complements of said types, and each type-bar also having guiding edges whereby it is guided toward the printing point, a stationary bearing in which one portion of said guiding edges on each type-bar is retained and moves, an individually-movable bearing for each type-bar in which another portion of said guiding edges is retained and moves, a series of paired key-operated levers, means whereby the operation of one of the levers of any pair drives a corresponding type-bar and causes one of said two types thereon to print, means whereby operation of the other lever of said pair also causes said corresponding type-bar to print, means whereby operation of said other lever simultaneously shifts said movable bearing of the operated type-bar and thereby causes the other one of said two types to print.
11. In a typewriting machine, the combination with a radial array of type-bars in front of said platen, each type-bar having a rectilinear movement from said array toward a common printing point, a plurality of types on each type-bar, a series of paired key-operated levers, each lever operable by pressing its own key, means whereby either lever of each pair operates a type-bar corresponding to said pair, and means whereby operation of one lever of each pair displaces the operated type-bar and causes the type corresponding to the operated lever to print, said last-mentioned means including a stop-device to limit said displacement and a yieldable connection between said one lever and the related type-bar, said one lever at the point of attachment of said connection having a movement in excess of the movement required for said displacement, which is thereby completed before the type-bar strikes.

nation of a series of type-bars, each having two types and uppercase complements of said types, and each type-bar also having guiding edges whereby it is directed towards the printing point, individual bearings for each type-bar, each bearing having two relatively shiftable portions in which the guiding edges of the type-bar are retained and move, a series of paired key-operated levers, means whereby the operation of one of the levers of any pair drives a corresponding type-bar and causes one of said two types thereon to print, means whereby operation of the other lever of said pair also causes said corresponding type-bar to be driven to the printing point, and means whereby operation of said other lever to print simultaneously shifts the relative positions of said portions of the bearing of the operated type-bar and thereby causes the other one of said types to print.

12 In a typewriting machine having a platen, the combination of a series of type-bars, each having two types and upper-case complements of said types, and each type-bar also having guiding edges whereby it is directed toward the printing point, said platen and said printing point having a relative movement of either to the other, 30 a stationary bearing in which one portion of said guiding edges on each type-bar is retained and moves, an individually-movable bearing for each type-bar in which another portion of said guiding edge is retained and moves, a movable type-guide at the platen whereby each type-bar is enabled to register its type at the printing point, a series of paired key-operated levers, means whereby the operation of one 40 of said levers of any pair drives a corresponding type-bar and causes one of said two types thereon to print, means whereby operation of the other lever of said pair also causes said corresponding type-bar to be driven to the printing point, means whereby operation of said other lever simultaneously shifts the movable bearing of the operated type-bar and thereby shifts the type-bar and causes the other one of said 50 two types to print, and means whereby operation of said other lever moves said type-guide co-relatively with the shifting of said type bar.

13. In a typewriting machine, the combination with a type-bar having a plurality of types thereon and also having guiding edges whereby it is directed toward the printing point, of a stationary bearing in which one portion of said guiding edges is retained and moves, a movable bearing for said type-bar in which another portion of said guiding edges is retained and moves, means for actuating said type-bar, said means including a pair of key-operated levers, and means whereby operation of one

of said levers shifts said movable bearing to direct the type-bar for printing from the type corresponding to the last-mentioned lever.

14. In a typewriting machine having a platen, the combination with a plurality of type-bars, each having a plurality of types thereon and each type-bar having guiding edges whereby it may be guided in a substantially rectilinear direction towards said platen, of means for disposing said type-bars in a radial array wherefrom each type bar may be projected toward a common printing point, said means including two arcuate and radial arrays of bearings in which the guiding edges of said type-bars move, the bearings in one arcuate array being fixed and the bearings in the other arcuate array being individually shiftable, a series of key-operated levers, means whereby operation of any one of said levers causes a corresponding type-bar to be projected towards said platen to print from a type corresponding to said lever, means whereby each type-bar is operable by a plurality of said levers, and means whereby operation of any one of certain ones of said levers simultaneously shifts the movable bearing of the operated type-bar and thereby selects said corresponding type.

15. In a typewriting machine having a platen, the combination with a series of slidable type-bars, each having a plurality of types, said type-bars being arranged about a printing point in a radial and arcuate array whence each type-bar may be projected towards said platen, of a transversely movable member for each type-bar in which a portion thereof slides, said members being arranged in an arcuate array near the type-ends of the type-bars, a pivoted shift-lever for each movable member, having one arm operatively connected to said member, mechanism for actuating said type-bars including a series of paired key-operated levers, and means for connecting one lever of each pair to the other arm of the shift-lever, said means including a resilient connection operable to compensate for variation in operative movements between said shift-lever and the actuating key-lever.

16. In a type-action for a typewriting or similar machine, the combination with a type-bar having a plurality of types thereon, each type-bar being substantially elongate and having longitudinal guiding edges whereby it is directed toward a printing point, of stationary bearings in which one portion of said guiding edges moves, a member normally stationary but individually movable relatively to said stationary bearings, said member having bearings in which another portion of said guiding edges moves, a normally stationary but movable impression-registering type-guide, a pair of

- key-operated levers, means whereby either lever may operate said type-bar to print, means whereby one of said levers also moves said member to shift the alignment of said bearings and thereby change the direction of movement of said type-bar, so that the type corresponding to said lever will print, and means whereby the change of said direction is accompanied by a co-relative shifting of said type-guide.
17. In a typewriting machine having a revolute platen movable relatively to a printing point, the combination with a series of type-bars, each type-bar having elongate guiding edges for directing its movement towards said printing point, and a plurality of types on each type-bar, of means for disposing said type-bars in a radial and arcuate array about said printing point, said means including a fixture, lateral guides for the type-bars, stationary bearings in said fixture wherein a portion of the guiding edges of each type-bar moves, an individually-movable member for each type-bar having bearings in which another portion of said guiding edges moves, each member being movably mounted in said fixture at the side of its type-bar, a series of paired key-operated levers, means whereby either lever of any pair may cause a type-bar to print, a fixedly pivoted shift-lever for each movable member and connected thereto, a stop-device for limiting the movement of said movable member, a yieldable connection between the other end of each shift-lever and one lever of each key-operated pair, a type-impression-registering guide, a universal bar, means connecting said guide and said universal bar, and means for causing said bar to be operated and said guide thereby shifted when the key-operated lever connected to said movable member is operated.
18. In a typewriting machine having a platen, the combination with a series of type-bars having a plurality of types thereon, and each type-bar movable endwise towards said platen to print, and a series of paired key-levers, of means whereby one lever of any pair may operate a type-bar common to said pair, stationary means for guiding the key-actuated end of said type-bars, individual transversely shiftable means for guiding the type-end of said bar, and means operative by the other lever of each pair to shift said shiftable means to change the angular direction of the associated type-bar to the typing position.
19. In a typewriting machine having a platen, the combination with a series of vertically-disposed, horizontally-reciprocable type-carriers, each carrier having a plurality of types, of a pair of key-levers for each type-carrier, one key having a positive connection operative to reciprocate the type-bar to type, and the other key having a resilient connection operative to case-shift the type-carrier to present a different type on the carrier to the typing position, the resiliency of the latter connection justifying the two movements of the type-carrier towards the typing position.
20. In a typewriting machine having a platen, the combination with a vertically-disposed, horizontally-reciprocable, key-actuated type-carrier having a plurality of types, of means operable to direct the path of said carrier to present the different types thereon to a common printing point on the platen, said means including stationary guides at one end of the carrier, a case-shift reciprocable guide for the opposite end of the carrier, a type-carrier-registering guide reciprocable at the typing position, and a case-shift key operatively connected to reciprocate both guides in unison.
21. In a typewriting machine having a platen, the combination with a vertically-disposed, horizontally-reciprocable, key-actuated type-carrier having a plurality of types, of means operable to direct the path of said carrier to present the different types to a common printing point on the platen, said means including stationary guides at one end of the carrier, and a case-shiftable guide for the opposite end of the carrier, said case-shiftable guide including a slot through which the type-carrier reciprocates.
22. In a typewriting machine having a platen, the combination with a vertically-disposed, horizontally-reciprocable, key-actuated type-carrier having a plurality of types, of means operable to direct the path of said carrier to present the different types to a common printing point on the platen, said means including stationary guides at one end of the carrier, and a case-shiftable guide for the opposite end of the carrier, both guides so arranged that the stationary guides become fulcrums between which the type-carrier rocks into alignment with the shiftable guide when the latter is case-shifted.
23. In a typewriting machine having a platen, the combination with a series of horizontally-reciprocable type-carriers, each provided with upper and lower case types, and a key-lever operatively connected to reciprocate each carrier to type, of means for variably directing each carrier to the typing position of the platen, said means including an individual vertically-reciprocable case-shiftable guiding support for each carrier, and a shift-key operatively connected to reciprocate each guide.
24. In a typewriting machine having a platen, the combination with a series of horizontally-reciprocable type-carriers, each provided with upper and lower case types, and a key-lever operatively connected to recipro-

- cate each type-carrier, of means for variably directing each carrier to the typing position of the platen, said means including a vertically-reciprocable supporting guide for the 5 type-end of each carrier, case-shift stops for each guide, and a case-shift key operatively connected to vibrate each guide between said stops to positively present either type-face to the typing position.
- 10 25. In a typewriting machine having a platen, the combination with a series of horizontally-reciprocable type-carriers, each provided with upper and lower case types, and a key-lever operatively connected to each 15 type-carrier, of means for variably directing the type on each carrier to the typing position of the platen, said means including a guide reciprocable transversely to the path of the carrier to change the angular path of 20 the carrier in typing, stops to limit the reciprocation of said guide and align each type to the platen, a case-shift key for each guide, and a connection intermediate each guide and its key permitting said key to finish its 25 stroke after said guide has been brought to a state of rest by the stops.
26. In a typewriting machine having a platen, the combination with a series of horizontally-reciprocable type-bars, each bar 30 having upper and lower case types and a series of key-levers, one lever operatively connected to reciprocate each bar to type, of key-actuated means for variably directing each type-bar to the typing position of the 35 platen, to present either case type, said means including a fixed guide common to one end of all the type-bars, an individual vertically-reciprocable case-shiftable guide-support for the type-end of each type-bar, and a case-shiftable type-registering guide at the typing position of the platen common to all the 40 type-bars, the printing position of the types on each type-bar coinciding with the printing positions of the types on all the 45 remaining type-bars.
27. In a type-writing machine having a platen, the combination with a series of horizontally-reciprocable type-bars, each bar having upper and lower case types and a series of key-levers, one lever operatively 50 connected to reciprocate each bar to type, of means for variably directing each type-bar to the typing position of the platen, to present either case type, said means including a fixed guide common to one end of all the type-bars, an individual vertically-reciprocable case-shiftable guide-support for the type-end of each type-bar, a universal type-registering guide case-shiftable at the typing position of the platen, and a series of 60 case-shift key-levers, one key-lever operatively connected to each case-shiftable support to simultaneously case-shift the universal type-registering guide.
28. In a typewriting machine having a 65 platen, the combination with a series of horizontally-reciprocable type-bars, each bar having upper and lower case types and a series of key-levers, one lever operatively 70 connected to reciprocate each bar to type, of means for variably directing each type-bar to the typing position of the platen, to present either case type, said means including a fixed guide common to one end of all the type-bars, an individual vertically-reciprocable case-shiftable guide-support for the type-end of each type-bar, a universal type-registering guide at the typing position of the platen, a series of case-shift key-levers, one key-lever operatively connected to each 75 case-shiftable type-bar support, and connections with each case-shiftable type-bar guide-support operative to simultaneously case-shift the universal type-registering guide, so that the typing position of the types on each 80 type-bar will coincide with the typing positions of the types on all of the remaining type-bars.

BENJAMIN M. DES JARDINS.
